UNITED STATES PATENT OFFICE.

JOHN A. PILCHER, OF ROANOKE, VIRGINIA.

DRAFT CONNECTION.

Application filed September 1, 1922. Serial No. 535,772.

This invention relates to railway cars and has among its objects to provide improved means for the rotative engagement of a coupler yoke with a coupler and with a cushioning mechanism. In the usual draft mechanism of railway cars the coupler yoke is subjected to lateral bending stresses when the pull on the coupler is out of line with the longitudinal axis of the yoke, which condition occurs when the car is on a curve. But by providing rotative engagement between the coupler and yoke and between the yoke and cushioning mechanism, these bending stresses are eliminated under the above conditions; namely, when the car is on a curve.

A further object of the invention is to provide a draft connection for railway cars in which the first cost is greatly reduced, as well as reducing the continued operating costs.

With the foregoing general objects in view, the invention consists of the formation, combination and arrangement of parts as set forth particularly in the appended claims, the various elements being co-ordinated to produce improvements generally in the art. The present application is a continuation in part of my co-pending application, Serial No. 462,082, filed April 18, 1921.

In the drawings, Fig. 1 is a plan showing a draft connection embodying my invention; Fig. 2 is an elevation, partly in section, thereof; Fig. 3 is a plan showing the method of placing the cushioning mechanism in position within the yoke before the mechanism is applied to the car.

Referring to these drawings the draft connection comprises a yoke with the upper and lower arms 1 and 2, respectively, and a vertically extending portion 3. Both the upper and lower arms are provided with vertically disposed slots 4, which have arc-shaped bearings 5 at their forward ends. The coupler butt 6 on its top and bottom surfaces is provided with circular extensions 7, each of which has laterally extending lugs 8 arranged at right angles to the longitudinal axis of the coupler. The cushioning mechanism 9 has an arc-shaped recess 10 in its rear face which receives an arc-shaped face on the vertically extending portion 3 of the yoke. Thus substantial pulling bearings are provided between the coupler and the yoke and between the yoke and cushioning mechanism and at the same time the coupler may

angle relative to the yoke and the yoke relative to the cushioning mechanism.

The rear face of the coupler butt 6 and the forward face of the follower block 11 preferably have arc-shaped faces 12 to permit the stresses in buffing to be transmitted directly from the coupler to the cushioning mechanism, regardless of the particular position to which the coupler may angle laterally with respect to the yoke. The follower block 11 is also provided with tangential surfaces 13 leading away from the arc-shaped face 12 which serve to guide the coupler butt back into position after it has been pulled away during draft.

The coupler and the yoke are connected by swinging the coupler at right angles to the yoke and turning it on its side. The coupler butt, when turned on its side, may be inserted between the upper and lower arms of the yoke and then, by using the rounded portion 14 of the coupler butt adjoining the trunnions 5, be brought back to its normal vertical position, when the lugs 8 will pass through the slots 4 in the upper and lower arms 1 and 2, respectively, of the yoke. The coupler may then be turned into longitudinal alignment with the yoke, thus locking the coupler to the yoke by means of the lugs 8. The front follower 11 is placed in position with its forward face 12 against the rear face of the coupler butt.

To insert the cushioning mechanism into position between the yoke arms the follower block 11 is rotated about the coupler butt and the cushioning mechanism placed with its rear face against the vertically extending portions of the yoke and its front face against the rear face of the follower block as shown in Fig. 3. From this position the cushioning mechanism and the follower block may be forced into their normal position, placing the cushioning mechanism under slight compression and causing the follower block to fit snugly against the coupler butt.

After inserting the cushioning mechanism the entire mechanism may be elevated into position on the car. Beneath the yoke are the carrier irons 15, which may be of any approved form, detachably fastened to the car frame. These carrier irons not only support the coupler butt, yoke and cushioning mechanism but also hold the lug 8 on the top of the coupler butt near the top cover plate 16 thereby limiting its vertical movement.

The rear faces of the forward draft sill stops 17 are slightly tapered, as is the front face of the follower block which comes in engagement with the stops. This will allow the front edges of the follower block to enter the space clear of the rear edges of the stops and thereby permit the easy application of the mechanism to the car after it has been assembled.

10 I have thus provided new and improved draft connections, of lower first cost, less weight, and greater economy of operation.

15 It is my intention to cover all modifications of the invention falling within the spirit and scope of the following claims.

I claim:

1. A coupler yoke comprising slotted upper and lower arms, a coupler having lugs on the top and bottom surfaces of the butt of greater lateral extent than the width of the slots in the yoke arms, said lugs being insertable and removable through said slots when the coupler is arranged at right angles to its normal position and turned on its side through an angle of approximately ninety degrees, a cushioning mechanism corresponding arc-shaped pulling surfaces on the coupler and yoke arms and on the yoke and cushioning mechanism, permitting, when locked together, lateral angling of the coupler relative to the yoke and also lateral angling of the yoke relative to the cushioning mechanism.

2. A coupler yoke having slotted upper and lower arms, arc-shaped bearings at the forward ends of the slots in said arms, a coupler, arc-shaped bearings on the top and bottom of the coupler butt engaging the arc-shaped bearings in the yoke arms and permitting lateral angling of the coupler relative to the yoke, a cushioning mechanism having an arc-shaped bearing in its rear face, a corresponding arc-shaped bearing on the yoke, permitting lateral angling of the yoke relative to cushioning mechanism, lugs on the coupler butt extending through said slots in the yoke arms, one of said lugs overlying a portion of the upper yoke arm and another of said lugs underlying a portion of the lower yoke arm when the coupler and yoke are in operative position, the coupler being removable from said yoke arms only when substantially at right angles thereto and turned on its side through an angle of approximately ninety degrees.

40 3. A coupler yoke having an arc-shaped vertically extending portion engaging an arc-shaped recess in a cushioning mechanism, thereby permitting lateral angling of the yoke relative to the cushioning mechanism, said yoke having vertical extending slots through

45 the upper and lower arms thereof, a coupler having projections on the top and bottom of its butt bearing against the forward ends of said slots and having a rotative engagement therewith for lateral angling, lugs on the pro-

jections having their long axis at right angles to the axis of the coupler engaging, respectively; the upper face of the upper arm and the lower face of the lower arm, the coupler and yoke being disengageable by rotation of one relative to the other to bring the lugs into position to permit their passage through said slots and then turning the coupler on its side through an angle of approximately ninety degrees.

4. A coupler yoke having a rotative engagement with a cushioning mechanism, the upper and lower arms of said yoke having vertically extending slots therethrough, a coupler having lugs on the top and bottom surfaces of the butt of greater lateral extent than the width of the slots in the yoke arms, said coupler having a portion of its butt rounded to permit the turning of same through an angle of approximately ninety degrees after it has been placed on its side between said slotted arms of the yoke whereby said lugs may be inserted or removed from said slots.

5. In a device of the character described, a coupler yoke having slotted upper and lower arms, a coupler having a slot and projection engagement with the forward ends of the yoke arms, a follower block, a cushioning mechanism, the connection between the upper and lower arms of said yoke having an arc-shaped surface bearing against a corresponding surface on the cushioning mechanism, permitting, respectively, rotary movement between the cushioning mechanism and the yoke and between the yoke and the coupler.

6. A coupler yoke comprising upper and lower arms with vertically extending slots therethrough, a coupler having projections on the top and bottom of the butt bearing against the forward ends of said slots and having a rotative engagement therewith for lateral angling, a cushioning mechanism, the connection between said yoke arms having an arc-shaped surface bearing against a corresponding surface on said cushioning mechanism, and having therewith a rotative engagement for lateral angling, a follower block having rotative engagement with said coupler to permit the easy insertion of the cushioning mechanism between said yoke arms.

7. A coupler yoke comprising upper and lower arms with vertically extending slots therethrough, a coupler having a slot and projection engagement with the forward ends of said upper and lower arms and capable of movement relative thereto, a cushioning mechanism, the connection between said yoke arms having an arc-shaped surface with a bearing upon the rear face of the cushioning mechanism, the butt of said coupler terminating in an arc-shaped surface, and a follower having its forward face formed to cooperate with the rear face of said coupler butt.

8. A coupler yoke comprising upper and

- lower arms with vertically extending slots therethrough, a coupler having a slot and projection engagement with the forward ends of said upper and lower arms, a cushioning mechanism, the connection between said yoke arms having an arc-shaped surface engaging a corresponding surface on said cushioning mechanism, the butt of said coupler being so formed that all points on its rear surface, 5 which lie in the same horizontal plane, move on the same circular arc when lateral movement of said coupler takes place, a follower having its forward face formed to cooperate with the rear face of said coupler butt, whereby 10 said follower may rotate about said coupler butt to permit the easy insertion of said cushioning mechanism between said yoke arms.
9. A coupler yoke comprising upper and lower arms with vertically extending slots therethrough, a coupler having a slot and projection engagement with the forward ends of said upper and lower arms, a cushioning mechanism, the connection between said yoke arms having an arc-shaped surface engaging 15 a corresponding surface on said cushioning mechanism, the butt of said coupler being so formed that all points on its rear face lie in a surface of revolution, a follower having its forward face formed to cooperate with the rear face of said coupler butt, whereby said follower may rotate about said coupler butt to permit the easy insertion of said cushioning mechanism between said yoke arms.
10. A coupler yoke comprising upper and lower arms with vertically extending slots therethrough, a coupler having a slot and projection engagement with the forward ends of said upper and lower arms, a cushioning mechanism, the connection between said yoke arms having an arc-shaped surface engaging 20 a corresponding surface on said cushioning mechanism, the butt of said coupler being so formed that any horizontal plane passed through its rear face will cut therefrom a portion of a circle, a follower having its forward face formed to cooperate with the rear face of said coupler butt, whereby said follower may rotate about said coupler butt to permit the easy insertion of said cushioning mechanism between said yoke arms.
11. A coupler yoke comprising slotted upper and lower arms, a coupler having lugs on the top and bottom surfaces of the butt of greater lateral extent than the width of the 25 slots in the yoke arms, said lugs being insertable and removable through said slots when the coupler is arranged at right angles to its normal position and turned on its side through an angle of approximately ninety degrees, corresponding arc-shaped pulling surfaces on coupler and yoke arms permitting, when the yoke and coupler have been locked together, lateral angling of the coupler relative to the yoke.
12. A coupler yoke having slotted upper and lower arms, arc-shaped bearings at the forward ends of the slots in said arms, a coupler, lugs on the top and bottom of the coupler butt having arc-shaped bearings engaging the arc-shaped bearings in the yoke 30 arms and permitting lateral angling of the coupler relative to the yoke, one of said lugs overlying a portion of the upper yoke arm and another of said lugs underlying a portion of the lower yoke arm when the coupler and yoke are in operative position, the coupler being removable from said yoke arms only when substantially at right angles thereto and turned on its side through an angle of approximately ninety degrees.
13. A coupler yoke having upper and lower yoke arms with vertically extending slots therethrough, a coupler, projections on the top and bottom of the coupler bearing against the forward ends of said slots and having a 35 rotative engagement therewith for lateral angling, lugs on the projections having their long axis at right angles to the axis of the coupler engaging, respectively, the upper face of the upper arm and the lower face of the 40 lower arm, the coupler and yoke being disengageable by rotation of one relative to the other to bring the lugs into position to permit their passage through said slots and then turning the coupler on its side through an angle of approximately ninety degrees.
14. A coupler yoke having slotted upper and lower arms, a coupler having lugs on the top and bottom surfaces of the butt of greater 45 lateral extent than the width of the slots in the yoke arms, said coupler having a portion of its butt rounded to permit the turning of same through an angle of approximately ninety degrees after it has been placed on its side between said slotted arms of the yoke 50 whereby said lugs may be inserted or removed from said slots.
15. A coupler yoke having slotted upper and lower arms, a coupler, the butt thereof having a slot and projection engagement with the forward ends of the yoke arms, a cushioning mechanism, and a front follower, said front follower being rotative about said coupler butt to permit the easy insertion of the 55 cushioning mechanism.
16. A coupler yoke having a slotted upper and lower arms, a coupler, the butt thereof having a slot and projection engagement with the forward ends of the yoke arms, a cushioning mechanism, a front follower, the butt 60 of said coupler being so formed that all points on its rear surface lie in a surface of revolution, the forward face of said front follower being formed to cooperate with the rear face of said coupler butt, whereby said front follower may rotate about said coupler butt to permit the easy insertion of said cushioning mechanism.
17. In a draft rigging, the combination with a slotted yoke, of a coupler, lugs formed 65

thereon and adapted to extend through the said yoke slots, heads on said lugs, said heads being equal in width to the said yoke slots, and means to permit the separation of said yoke and coupler by a plurality of rotations without spreading of said yoke arms.

18. In a draft rigging, the combination with a coupler, of a slotted yoke, means for pivotally connecting said coupler and yoke, said means comprising oppositely disposed headed lugs formed on said coupler and adapted to engage within said yoke slots, said coupler being further provided with rounded edge faces adjacent said lugs, said lugs being adapted to be freely entered and removed from said yoke only by a plurality of rotations of said coupler, at least one of said rotations being about the longitudinal axis thereof.

19. In draft mechanism, the combination of a yoke, a coupler, means for operatively connecting said yoke and coupler whereby there may be radial action at the point of connection therebetween, and draft gear operatively connected to said yoke whereby when there is a pulling force exerted on the coupler there may be a limited unrestrained radial action at the rear point of contact between said draft gear and yoke.

20. In draft mechanism, the combination of operatively associated coupler, yoke and draft gear, means for operatively associating said coupler, yoke and draft gear whereby under certain operative conditions there may be an appreciable radial action between the yoke and gear and between the yoke and coupler for facilitating the taking of curves.

21. In draft mechanism, the combination of a yoke, a coupler pivotally connected thereto, and draft gear operatively connected to the rear of the yoke whereby when there is a pulling force exerted on the coupler there may be a radial action at the rear point of contact between said draft gear and yoke, and whereby when the track curvature increases beyond a certain amount there will be additional radial action between said yoke and coupler.

22. In draft mechanism, the combination of a yoke, a coupler pivotally connected thereto, and a draft gear, a portion of said draft gear and of said yoke having a pivotal relationship in the form of cooperating concave and convex surfaces for facilitating radial action of the coupler, there being a pivotal connection between the coupler and yoke for facilitating radial action of the coupler with respect to the yoke.

23. In draft mechanism, the combination

of a yoke, a coupler, and draft gear, the rear of the draft gear having a member with a concave surface, the rear of the yoke having a cooperating convex surface whereby there may be radial action about said cooperating concave and convex surfaces, said coupler and yoke being pivotally connected for permitting radial action of the coupler with respect to the yoke.

24. In draft mechanism, the combination of a yoke, a coupler, and draft gear, the front surface of the rear of the yoke having a curved surface, the rear member of said draft gear having a curved surface cooperating with the curved surface of said yoke for facilitating a radial movement of the yoke, there being a pivotal connection between the coupler and yoke for facilitating radial action of the coupler with respect to the yoke for facilitating the taking of curves.

25. In draft mechanism, the combination of a vertical plane yoke, a coupler, and draft gear, the front face of the rear of said yoke having a curved surface, the rear member of said draft gear having a curved surface, cooperating with said other curved surface for facilitating radial action of the yoke, said coupler having a pivotal connection with respect to said yoke to permit radial action of said coupler for facilitating the taking of curves.

26. In draft mechanism, the combination of a vertical plane yoke, a coupler, draft gear, the front face of the rear of said yoke having a curved surface, the rear member of said draft gear having a curved surface cooperating with said other curved surface for facilitating radial action of the yoke, said coupler having pivotal connection with respect to said yoke to permit radial action of said coupler for facilitating the taking of curves, the coupler butt having a rear curved surface, and a front follower having a cooperating curved surface for facilitating centering of the coupler.

27. In draft mechanism, the combination of a yoke, a coupler connected thereto whereby there may be radial action at the point of connection therebetween, means for operatively connecting said draft gear to said yoke whereby when there is a pulling force exerted on the coupler there may be radial action at the rear point of contact between said draft gear and yoke, said coupler having a butt the rear surface of which is curved, and a front follower having a cooperating curved surface for facilitating centering of said coupler.

JOHN A. PILCHER:
